UNITED STATES PATENT OFFICE.

EDWARD V. WURTS, OF PITTSBURGH, PENNSYLVANIA, ASSIGNOR TO STEEL UTILITIES,
INCORPORATED, A CORPORATION OF NEW YORK.

METAL-PUNCHING MACHINE.

1,241,269.

Specification of Letters Patent. Patented Sept. 25, 1917.

Application filed September 19, 1916. Serial No. 120,921.

To all whom it may concern:

Be it known that I, EDWARD V. WURTS, a citizen of the United States, residing at Pittsburgh, in the county of Allegheny and 5 State of Pennsylvania, have invented certain new and useful Improvements in Metal-Punching Machines, of which the following is a specification.

The invention relates to machines and 10 mechanisms for automatically positioning or spacing and punching rivet holes in structural beams and like work, and more especially in certain aspects thereof to means for coöperating with a perforated distance 15 record sheet to control the travel and stopping of the beam and the operation of the punching means thereon, together with means for feeding forward the perforated distance record sheet as desired.

20 Objects and advantages of the invention will be set forth hereinafter in part, and in part will be obvious herefrom, the same being attained and realized through the means and combinations set out in the appended 25 claims.

The invention consists in the novel parts, constructions, arrangements, combinations and improvements herein shown and described.

30 The accompanying drawings herein referred to, and forming a part hereof, illustrate one embodiment of the invention, and with the description, serve to explain the principles thereof.

35 Of the drawings:

Figure 1 is an end elevation of a machine constructed in accordance with the principles of the invention, and looking at Fig. 2 from the bottom, and at Fig. 3 from the 40 right;

Fig. 2 is a top plan of the machine shown in Fig. 1;

Fig. 3 is a side elevation looking at Figs. 1 and 2 from the left;

45 Fig. 4 is a transverse section, on an enlarged scale, taken perpendicularly to the plane of the paper on the line A—B of Fig. 1;

Fig. 5 is a somewhat different form of 50 the mechanism shown at the upper end right hand parts of Fig. 1;

Fig. 6 is a fragmentary detail of a distance record sheet; and

Fig. 7 is a diagrammatic representation

of parts of the machine and of their circuit 55 connections.

A shape or beam punching machine controlled by a distance record sheet, adapted to provide and control widely varying successive feeds or distances of travel of the 60 shape or like work, such as are required to properly and accurately position the rivet holes in the shape, is shown in application Ser. No. 814,380, of T. P. Payne, filed January 26, 1914. My invention provides an improved machine of the kind described, and in connection with such a machine, means for correlating and safeguarding the alternate feeds of the shape and the distance record sheet, as well as other added features 70 and improvements, as will appear herefrom.

Referring by way of example to the illustrated embodiment of the accompanying drawings of the means and devices coöperating with the distance record sheet to 75 control the shape traveling and stopping means, and for feeding the distance record sheet in harmony with the shape traveling and stopping means and the shape punching means, side frame members 1 and 2 are provided, extending upwardly from base members 3 and 4, which base members are adapted to rest upon a table or like support. Means are provided by the invention coöperating with the perforations 5 in the distance record sheet 6 to control the travel and positioning of the beams or like work, and in the embodied form, said means are electrically controlled and operated. In such embodied form, a support 10, preferably 80 of wood or other nonconducting material, is disposed horizontally and transversely between the upright frame members 1 and 2. The ends of said support 10 rest upon brackets 11 and 12, which extend inwardly from 85 the frame members 1 and 2, the support 10 being attached to the brackets in a suitable manner as by screws 13 and 14, respectively. Mounted in the support 10 are a plurality of insulated electrical contacts, arranged in 100 a bank along the support 10 a distance equal to the width of the space assigned to perforations in the distance record sheet 6. These contacts are also arranged in staggered relation for economy of width in the 105 record sheet and of space in the machine, and as shown, they are staggered three deep (Figs. 2 and 4), extending for the greater

part of the length of the support 10 (only a few of the contacts being shown in Figs. 1, 2 and 5, the remainder being preferably of the same structure and arrangement.

5 The contacts 15 are shown, respectively, with heads contained within recesses in the upper part of the support 10, the upper surface of the contacts being preferably flush with the top of the support. The contacts 10 have downwardly extending rods 16 of less diameter passing through the support 10, each contact thereby having a seat in said support. The lower end of each rod 16 is preferably screw-threaded and is provided 15 with locking nuts 17, to each set of which is connected an electrical wire 18 belonging to a machine-controlling circuit.

Coöperating with the support 10 is a bar or carrier 20 carrying a group of contacts 25 which coöperate with the contacts 15, through perforations made in the distance record sheet 6, to selectively close the various circuits corresponding to, and required for, the particular distance reading of the machine as represented by the perforations in the distance record sheet.

As embodied, the carrier 20 is cut away centrally, and in such cut away portion is located a metal plate or block 21, having outwardly extending flanges 22 and 23 resting upon and included within correspondingly shaped undercut portions of the carrier 20. Block 21 is held in position by suitable means such as bolts 24. In the block 21 are 30 mounted in series a plurality of spring-pressed contact pins 25 adapted to contact with the corresponding contacts 15 when the perforations in the controlling sheet so permit.

40 The contacts 25 and the coöperating contacts 15 are arranged and positioned to correspond to any group of perforations which may occur in the distance record sheet for any desired distance reading, whether it be 45 for a travel of a fraction of an inch or of many feet, inches and a fraction, the feed of the sheet being definite and independent of the successive amounts of travel of the beam to be punched. In the illustrated form 50 the sets of contacts 15, 25 are arranged in three staggered rows (see Figs. 2 and 4) and the perforations in sheet 6 are correspondingly arranged. The forward feed is the distance between two of the transverse lines 72, marked on the distance record sheet 55 in Fig. 6.

As embodied, the block 21 has a plurality of cylindrical apertures therein of relatively large diameter opening on the underside of said block, and communicating with the top side of the block by openings of smaller diameter. In the larger openings are the heads 25 of the coöperating contacts the respective heads being connected to rods 26, which rods 60 extend outwardly through and substantially

fill the apertures of smaller diameter at the top of the block 21. In compression between the heads 25 of the contacts, respectively, and the inner end of the larger part of the apertures are coiled springs 27, which springs tend to press downwardly or outwardly the contact heads 25 in Fig. 4. The rods 26 are preferably screw-threaded, and are provided with lock nuts 28 which limit their downward movement. A single electrical circuit wire 29 is preferably connected to the metal block 21 by means of one of the bolts 24.

75 The springs 27 press the contact heads 25 against the distance record sheet 6, but the contact heads cannot pass therethrough unless there is a perforation at that point in the distance record sheet. At the right hand in Fig. 4 is shown a contact 25 passing through a perforation in the record sheet 80 and thus closing the circuit through the corresponding contact 15, while the two remaining contacts shown at the center and left in Fig. 4 are held in the circuit opening, or dead circuit, position by the interposition 85 therebetween of an unperforated portion of the distance record sheet 6.

90 Means are provided for lifting the contact carrying bar 20, and in accordance with certain features of the invention this is done 95 automatically at each successive feeding forward of the distance record sheet 6 by the machine immediately upon the completion of each perforation or punching of the beam.

95 In the embodied form of such means, the bar 20 is pivotally supported or hinged at one end (at the left in Figs. 1 and 2) by means of apertured plates 30 attached to the bar, and located between two upwardly extending brackets 31 and 32 fixed to the 100 machine frame, and likewise apertured. A rod 33 extends therethrough to form a hinge or pivoted support for the bar 20. At its opposite end (at the right in Figs. 1 and 2) the supporting bar 20 is connected by suitable means, such as the notched plate 34 105 to a rod 38 fixed to the core 41 of a solenoid 42.

110 The notched plate 34 straddles the vertically disposed screw-threaded rod 38 between nuts 39 and 40 threaded on said rod. The rod 38 is connected to the core 41 of solenoid, the winding being indicated by 115 42. The core 41 is held in a decentered downward position (in Fig. 1) by coil spring 43 which spring is in compression between the solenoid casing 44 and a disk 45 carried upon the bottom end of a rod 46, which rod is fixed to and extends downwardly from the bottom end of the solenoid core. Disk 45 may be held in place by a nut 47. The solenoid is operated by a 120 circuit which is controlled by the punching means or some associated mechanism. The solenoid is energized at the completion of 125 130

the punching operation, and its core 41 is thereby moved upwardly in Fig. 1 and downwardly in Fig. 5, lifting the bar 20 and its bank of spring-pressed contacts away 5 from the distance record sheet 6. The sheet 6 is thus left free, resting upon the flat reaches of the bands 67 and 69 with a plurality of the registering projections 68 and 70 engaging a plurality of the holes 71 in 10 the sheet 6. The sheet 6 is then fed forward one step by means later to be described. When the solenoid circuit is de-energized, the spring 43 brings the bar 20 down with the bank of contacts in position to coöperate 15 with the perforations which have been presented by the feeding up of the distance record sheet.

Means are provided for swinging the bar 20 well back to afford ample space by removal and replacement of successive distance record sheets. For this purpose, the notched plate 34 is preferably slidably mounted upon the bar 20 and as shown it slides longitudinally beneath cross pieces 35 25 and 36 fixed to the bar 20, and is provided with a finger piece 37. By this means the notched plate may be slid backwardly, and thereby be disengaged from its solenoid connection, and the bar 20 be free to be raised 30 by hand at any time as desired.

Means are provided for imparting an intermittent feed to the distance record sheet 6 to bring the successive distance readings into operative relation with the bank of 35 contacts so that the beam may be traveled or progressed through the machine for the successive distances between the different rivet holes or groups of rivet holes, said means operating in timed relation with the 40 punching mechanism. In the embodied form of such means, a shaft 60 is mounted in the side frames 1 and 2, said shaft carrying two wheels 61 and 62, the peripheries of said wheels having depressions or 45 recesses 66 formed therein, equally spaced apart about their circumferences. At the other end of the frames 1 and 2 is a shaft 63 having fixed thereon similar wheels 64 and 65, which likewise have in their peripheries depressions 66 equally spaced 50 about their circumferences. Running over the wheels 61 and 64 is a belt 67, preferably of flexible metal, in which belt is embedded a series of balls or like projections 68 55 equally spaced apart with the depressions 66 in the peripheries of the wheels. On the opposite side of the machine a belt 69 similar to 67 is also provided with balls or projections 70 embedded therein and similarly 60 spaced apart.

Referring to Fig. 6 the distance record sheet 6 has feeding apertures or perforations 71 arranged longitudinally along each edge thereof, said apertures being spaced 65 apart the same distance as the balls 68 and

70. In the distance record sheet shown in Fig. 6 the distance of a single feed is represented by the successive transverse lines 72, there being room therebetween for three sets of staggered perforations corresponding to the contacts 15 and 25. The underside of the bar 20, as shown at 73 and 74 is recessed, as is also the bar 10, to permit the passage of the balls 68 and 70. The balls 68 and 70 simultaneously engage with 75 a large number of the holes 71 at either side of the distance record sheet 6 and with a large number of the depressions 66 on all four of the wheels 61, 62, 64 and 65. There is thus provided a support of relatively 80 great extent along and at either side of the distance record sheet 6, each of said supports having a plurality of registering devices continuously in engagement with the perforations 71 in the record sheet and a 85 great number of registering devices in engagement with the registering recesses in the wheels of the mechanism, whereby the record sheet is kept in absolute alinement with the bank of contacts 15 and 25 at all 90 times.

Means are provided for imparting an intermittent feed to the distance record sheet 6 from one distance reading to the next, the same operating automatically in connection 95 with the operations of the punching machine, and being called into action at the completion of the punching operation. In certain aspects of the invention, said intermittent feed is secured in connection 100 with a continuous friction drive. As embodied there is fixed to the left hand end of the shaft 63 (Figs. 1 and 2) a ratchet wheel 80. A pawl-carrying arm 81 is mounted to swing upon shaft 63, a pawl 79 105 being mounted upon arm 81, the pawl engaging the ratchet wheel 80.

Pivotedly connected to the outer end of the arm 81 is a downwardly extending arm 82, which arm is also pivotally connected to a crank arm 83. The arm 83 is fixed to a shaft 84, which shaft extends horizontally and is journaled in supports 85 and 86. Fixed to rotate with shaft 84 are friction disks 87. Loose upon shaft 84 is a worm 115 wheel 88, which is pressed against the disks 87 by a spring 89 encircling the shaft 84. Spring 89 is in compression between a plate 90 which is fixed to the worm wheel, and a friction plate or collar 91 upon the shaft 120 84. The collar 91 is provided with a clamping screw 92 by which the collar may be positioned and the spring pressure thereby regulated. Meshing with the worm wheel 88 is a worm 93 on a horizontal shaft 94, 125 which shaft is journaled in supports 95 and 96, fixed to the support 85. The shaft 94 is driven either directly or by gearing from a motor 97.

The embodied mechanism just described 130

would tend to impart continuous rotation to shaft 84 through the friction clutch and thereby a continuous reciprocation to arm 81, and thus to continuously feed the distance record sheet 6. In the embodied form of mechanism for effecting an intermittent feed of the sheet 6 in time with the punching mechanism, there is provided a longitudinally slidable pin 98 engaging arm 83 upon its forward side. Pin 98 is mounted to slide in supports in a bracket 99, and is pressed into the path of the arm 83 by a spring 100, which spring is in compression between a collar 101 upon the pin 98 and a boss 102 upon the support 85. The pin 98 is fixed to the core 103 of a solenoid 104, the other end of the core 103 having a projecting rod 105 slideable in a support 106, the horizontal core being thus slidably supported within its winding and being yieldingly held in decentered position by spring 100. When the solenoid 104 is momentarily energized, the pin 98 is retracted out of the path of the arm 83, the arm 83 being thereby released for a single revolution, the pin 98 returning to stopping position before the arm 83 has completed its revolution. The pawl arm 81 is thereby given a single reciprocation, and its spring-pressed pawl 79 will feed forward the ratchet wheel 80, and impart a partial rotation to the shafts 60 and 63, and co-operating parts, thereby feeding forward the distance record sheet 6 the space of a single reading. The shaft 84 is under a continuous impulsion toward rotation from the continuously running motor 97, through the slip or friction drive between the worm wheel 88 and the disk 87, but the shaft 84 is held from rotation except when the arm 83 is released by the solenoid 104, thereby giving a uniform positive and reliable intermittent and timed feed for the distance record sheet.

In Fig. 5 of the drawings is shown a different form of mounting and raising means for the contact supporting bars 20, said bar being pivotally supported at its right hand end by means of lugs 111 fixed to the bar, and pivotally connected to links 110, which links are supported from a shaft 112 carried in an upwardly extending portion of the frame member 2. At the left hand end of bar 20 it is pivotally supported by means of lugs 114, fixed to the bar, and pivotally connected to arms 113, which arms are fixed to the bar 20. The arms 113 are fixed to shaft 115, which shaft is journaled in upwardly extending portions of the frame 1. Fixed to shaft 115 is an arm 116, having a loose pivotal connection with the rod 38, which rod is connected to the solenoid core 41, and operating in the manner already described.

Means are provided by the invention for safeguarding against any feeding movement

or release of the beam by the distance determining means while the distance record sheet is being fed forward for a new distance reading. In the embodied form of such means, the electrical circuits between the bank of contacts and the distance determining means are broken during the feeding forward of the distance record sheet 6, and the circuits are made when the feeding of the distance record sheet is completed. As 75 embodied the trunk circuit wire 29 is connected to a stationary switch member 120, mounted on the frame base 3. From the member 120 extends a contact piece 121. Contacts 122 are provided movable into and out of engagement with contact 121 to successively make and break the circuit 24, the contacts 122 moving in proper relation to the feed of the distance record sheet. For this purpose the contacts 122 are mounted on a block 80 123, which block is slidably mounted on a guideway 119 on the base 3. A wire of the circuit 29 is connected to block 123. Pivoted to block 123 is a link 124, which link is also pivoted to an arm 125 fixed to move 85 with arm 81 of the feeding mechanism for the distance record sheet. Thus at the beginning of the feeding of the distance record sheet through the actuation of arm 81, the circuit 29 for the entire bank of contacts 25 95 is broken between the switch members 121 and 122, and the circuit is not remade at that point until the close of the sheet feeding movement. The shape traveling and positioning means is thus unable to operate during the feed of the sheet, but is brought into operation immediately thereafter by the closing of the circuit 29 at 121—122 and, through the contacts which have formed 100 perforations in the record sheet 6, thereby 105 giving the corresponding travel and positioning of the shape relatively to the punching mechanism.

In the embodied form of means for correlating and synchronizing the traveling 110 and stopping and positioning for the shape, the punching thereof, and the feeding of the distance record sheet (see particularly Fig. 7), the contacts 15 and 25 are shown making the desired or selected circuits through the 115 distance record sheet 6. This electrically energizes the coils of contactors 140, which contactors control the operation and sequence of both the distance determining means and the punching mechanism. The 120 distance determining devices or mechanism is shown in Fig. 7 in a conventional manner, being represented by the coils of contactors 140, but such mechanism, so far as concerns many features of the invention, may be of 125 any suitable or approved form, and may be of the form shown in application Ser. No. 842,231 of L. A. Hawthorne, filed June 1, 1914. The shape is thus traveled the selected distance, is stopped in proper posi- 130

tion, and thereupon the rivet holes are punched therein.

When the punch operates, a cam 142 closes switch 143 upon the return stroke of the 5 punch. Switch 143 is in circuit 144, and the closing of the switch energizes solenoid 103, thereby retracting pin 98 and starting the feeding mechanism for the distance record sheet 6. Switch 121-122 is opened in the 10 manner hereinbefore described and cuts the current off from the contacts 25 and also de-energizes coil 145 of contactor 146, allowing it to close and thereby energize solenoid 42, to lift the bar 20 during the feeding forward 15 of the distance record sheet. When the distance record sheet 6 has advanced the space of a reading, the switch 121-122 is closed, thereby opening contactor 145 which deenergizes solenoid 42 and brings the contacts 25 20 into engagement with the distance record sheet 6 thereby energizing the selected circuits for the next distance of travel of the shape or like work, and also energizes the circuits controlling the selection of punches 25 and punch operating means.

From all the foregoing it will be understood that a machine has been provided embodying the objects of invention and the advantages herein set forth, together with 30 other objects and advantages. It will be further understood that changes may be made from the precise structure shown and described without departing from the principles of the invention and without sacrificing 35 its chief advantages.

What I claim as my invention and desire to secure by Letters Patent is:—

1. A distance controlling device for metal 40 punching machines including in combination a distance record sheet having spaced feeding perforations at the sides thereof, a plurality of wheels in alinement at each side of the distance record sheet, an endless band passing over the alined wheels at each side 45 and having projections engaging the feeding perforations in the distance record sheet, means including a pawl and ratchet mechanism for imparting intermittent rotation to said wheels and a friction drive and automatic release therefor.

2. A metal punching machine including in combination a bank of contacts, a perforate 55 distance record sheet coöperating therewith, and having series of spaced feeding holes at the sides, a shaft at one side of the bank of contacts and extending transversely and having wheels at either side of the distance record sheet, a shaft at the other side of said bank of contacts and having wheels at either 60 side of the distance record sheet, flexible bands extending over the wheels at either side and having spaced projections engaging the feeding holes in the distance record sheet and means including a friction drive and an 65 intermittently operating release and stop

therefor for imparting intermittent rotary movement to said wheels.

3. A mechanism coöperating with a distance record sheet having successive rows of perforations thereacross to control metal 70 punching machines and the like, including in combination means for presenting the distance record sheet substantially in a plane, a bank of coöperating contacts extending across the sheet and in yielding engagement 75 therewith, means for intermittently feeding forward the sheet substantially along said plane, and means for alternating the feeding movement with the feeding of the work in the controlled machine.

4. A mechanism coöperating with a distance record sheet having successive rows of perforations thereacross to control metal punching machines and the like, including in combination a series of contacts coöperating 80 with said sheet, and means for intermittently feeding the sheet forward, said means including an electro-magnetic device, and its circuit, the circuit being governed by the controlled machine.

5. A mechanism coöperating with a distance record sheet having successive rows of perforations thereacross to control metal punching machines and the like, including 85 in combination a series of contacts coöperating with said sheet, and means for intermittently feeding the sheet forward, said means including driving means and a release therefor operated by a solenoid and its circuit, the circuit being governed by the controlled 90 machine.

6. A mechanism coöperating with a distance record sheet having successive rows of perforations thereacross to control metal punching machines and the like, including in combination a series of contacts coöperating 100 with said sheet, and means for intermittently feeding the sheet forward, said means including traveling devices engaging with feeding holes in the sheet, a friction drive, and a release therefor comprising an electro-magnetic device with its circuit, the circuit being governed by the controlled 105 machine.

7. A mechanism coöperating with a distance record sheet having successive rows of perforations thereacross to control metal punching machines and the like, including in combination a series of contacts arranged 110 across the sheet and in yielding engagement therewith, means for presenting and feeding the sheet comprising traveling bands extending past the contacts and longitudinally of the sheets, said bands provided with projections engaging with feed holes in the sheet, 115 wheels driving said bands, and intermittent driving means for said wheels governed by the controlled machine.

8. A mechanism coöperating with a distance record sheet having successive rows of 120

perforations thereacross to control metal 5
punching machines and the like, including
in combination a series of contacts arranged
across the sheet and in yielding engagement
therewith, means for presenting and feeding
the sheet comprising traveling bands extending
past the contacts and longitudinally of
the sheet, said bands provided with projections
engaging with feed holes in the sheet,
wheels driving said bands, and intermittent
driving means including a pawl and ratchet
device, a friction drive and a release.

9. A mechanism coöperating with a distance
record sheet having successive rows of
15 perforations thereacross to control metal
punching machines and the like, including
in combination a series of contacts arranged
across the sheet and in yielding engagement
therewith, means for presenting and feeding
20 the sheet comprising traveling bands ex-
tending past the contacts and longitudinally
of the sheet, said bands provided with pro-
jections engaging with feed holes in the
sheet, wheels driving said bands, and inter-
mittent driving means including a pawl and
25 ratchet device, a friction drive and a release
operated by the controlled machine.

10. A mechanism for controlling a metal
punching machine for structural shapes and
30 the like, including in combination distance
determining means for traveling and stop-
ping the shape relatively to the punch to
locate the rivet holes at the proper points
in the shape, and mechanism coöperating
35 with a distance record sheet to successively
set the distance determining means for the
successive required distances, means for in-
termittently feeding the distance record
sheet forward between successive settings of
40 the distance determining means, and means
for insuring alternate operation of the sheet
feeding means and the distance determining
device.

11. A mechanism for controlling a metal
punching machine for structural shapes and
45 the like, including in combination electrically
operated distance determining means for
traveling and stopping the shape relatively
to the punch to locate the rivet holes
50 at the proper points in the shape, electrically
operated mechanism coöperating with a dis-
tance record sheet to successively set the dis-
tance determining means for the successive
55 required distances, means for intermittently
feeding the distance record sheet forward
between successive settings of the distance
determining means and circuit controlling
means for insuring alternate operation of
60 the sheet feeding means and the distance
determining device.

12. A mechanism coöperating with a dis-
tance record sheet having successive rows of
65 perforations thereacross to control metal
punching machines and the like, including
in combination a series of yielding electrical
contacts arranged in a bank across the dis-
tance record sheet and representing distance
70 denominations and values, and means in-
cluding an interacting release and stop gov-
erned by the controlled machine for feeding
the distance record sheet forward from one
transverse row of holes to the next after each
75 actuation of the controlled machine.

13. A mechanism coöperating with a dis-
tance record sheet having successive rows of
80 perforations thereacross to control metal
punching machines and the like, including in
combination a series of yielding electrical
contacts arranged in a bank across the dis-
tance record sheet and representing distance
85 denominations and values, and means in-
cluding a shaft separate from but governed
by the controlled machine for feeding the
distance record sheet forward from one
transverse row of holes to the next after
90 each actuation of the controlled machine.

14. A mechanism coöperating with a dis-
tance record sheet having successive rows of
95 perforations thereacross to control metal
punching machines and the like, including
a friction drive, and a release therefor com-
prising an electro-magnetic device with its
circuit, the circuit being governed by the
controlled machine.

15. A mechanism coöperating with a dis-
tance record sheet to control a metal punch-
ing machine, the sheet having successive
rows of perforations arranged across the
sheet, the rows being equally spaced apart
100 along the sheet, said mechanism including
in combination a bank of coöperating con-
tacts arranged across the sheet and in yield-
ing engagement therewith, means for inter-
mittently feeding forward said sheet a fixed
105 distance from one transverse series of per-
forations to the next, a series of coils control-
ling the distance determining means of the
punching machine and in circuit with the
respective contacts in said bank, and means
110 for alternating the feeding movement of the
sheet with the feeding movement of the
work in the punching machine.

In testimony whereof, I have signed my
name to this specification, in the presence of
two subscribing witnesses.

EDWARD V. WURTS.
